LUMINAIRE

Vearl S. Wince, Newark, Ohio, assignor to Holophane
Company, Inc., New York, N.Y., a corporation of
Delaware

Filed May 7, 1965, Ser. No. 85,181

Term of patent 14 years

(Cl. D48—23)

FIG. 1 is a perspective view showing the overall configuration of a luminaire showing my new design;

FIG. 2 is a top plan view of the luminaire shown in FIG. 1;

FIG. 3 is a side elevation view of the luminaire shown in FIG. 1;

FIG. 4 is a bottom plan view of luminaire shown in FIG. 1;

FIG. 5 is an end elevational view of a luminaire shown in FIG. 1; and

FIG. 6 is a section view taken along lines 6-6 of FIG. 2.

I claim:

The ornamental design for a luminaire, substantially as shown.
